UNITED STATES PATENT OFFICE.

PETER BOHLING, OF HAMBURG-STEINWARDER, GERMANY, ASSIGNOR, BY MESNE ASSIGNMENTS, TO SOCIETE ANONYME POUR TOUS APPAREILLAGES MÉCANIQUES, (SATAM), OF LEVALLOIS-PERET, FRANCE.

DISPENSING APPARATUS.

Application filed April 25, 1927, Serial No. 186,542, and in Germany May 10, 1926.

The object of the present invention is to prevent the drawing off or tapping of oil, liquid fuel or other liquids from tanks or barrels or other closed vessels in shops for example by retailers and others who have undertaken to only sell the supplies of a particular firm. The retailers in such cases are not expected to provide the tanks and pumps or the like for containing and supplying the prescribed quantities as the wholesale distributors supply these tanks and pumps to merchants or to shops and they are marked with trade marks or brands or labels or other means of identification so that the purchaser can always see that he is given the oil for example that he requires as supplied by a particular distributor.

At the present time there is nothing to prevent a merchant selling oil which has not been supplied by the distributor whose mark appears on the tank or pump, so that the purchaser may be surreptitiously given an oil of unknown origin or of inferior quality. This can be done by the retailer either filling up the tank belonging to a well known distributor with some other distributor's oil, or by applying the pump supplied by the well known distributor to a tank filled with oil of inferior quality. In the latter case the customer's suspicions are not aroused since the pump bears the mark or label of the well known distributor.

Both these malpractices will be prevented by the apparatus of the present invention. This apparatus aims on the one hand at making it impossible that the tank supplied by and bearing the mark of a well known distributor can be filled through the outlet with which the pump is to be connected and on the other hand the pump is so constructed that it can only operate in connection with this particular tank and it will be inoperative with other tanks.

With regard to the surreptitious filling of the tank with oil, only the opening to which the pump is to be connected that is the outlet opening need be taken into consideration, as the filling opening proper is fitted with a closure provided with a lead seal. The introduction of oil through the outlet opening is impossible in apparatus according to this invention because this outlet communicates with a pipe projecting down into the tank and provided with an automatic or non-return

valve. In order that the pump cannot be used with any tank other than the one to which it is properly associated the suction valve of the pump is omitted and means are provided for preventing the subsequent application of a suction valve directly to the pump. Now if the pump without a suction valve is connected to the correct tank the aforesaid pipe communicating with the outlet opening of the tank forms a suction pipe and its valve the suction valve for the pump so that with such a combination the pump is operative.

In the accompanying drawing Figure 1 is a vertical section of a tank constructed according to the present invention, and

Figure 2 a vertical section of a pump to be used in connection with the tank shown in Figure 1.

Figure 3 is a vertical section of the complete apparatus, the pump being connected to the tank.

The tank *a* which may be cylindrical is generally made of sheet iron, the inlet or filling opening being closed by a closure *b*, that may be provided with a lead seal. One of the end walls, preferably the top, is provided with the outlet opening in which is fitted a connecting socket *c* adapted to be connected with the pump *d*, which where it is to be connected to the tank as at *h* is provided with means for connection to the socket *c* by any suitable means. In the construction shown the connecting plug *h* is provided with external screw threads, and the socket *c* with internal screw threads engaging with the external screw threads of the plug *h*. The socket *c* is secured to an open ended tube *e* projecting down nearly to the bottom of the tank and provided there with a valve *f* constructed to open upwardly but closing downwardly to prevent liquid from being admitted into the tank through the tube *e*, the valve casing *f'* having openings *f''* near the bottom of the tank. Any attempt therefore to admit liquid into the tank through the outlet opening *c* will be prevented by the valve *f*.

The pump *d* that is provided with an adjustable piston *g* will be connected to the tank by screwing the plug *h* into the socket *c* but having no suction valve it is inoperative by itself.

To prevent the pump *d* being subsequently provided with a valve, for instance a ball that might close the suction port or channel *h'*

in the plug h , this channel h' at its upper end, that is to say where it merges into the cylinder is provided with incisions k or with projections k' so that if a valve or ball were to be dropped into the pump the port or channel h' would not be closed thereby.

Thus it will be obvious that the pump d in any event will be inoperative except when connected to the proper tank shown in Fig. 10 1 in which case the pipe e and the valve f will constitute its suction pipe and its suction valve, so that when both parts are combined, as shown in Fig. 3 the pump will be operative.

15 To allow air to enter the tank from above when drawing off the liquid a small channel i is provided in the connecting plug h of the pump that communicates with the inside of the tank through the small opening m in the 20 socket c .

I claim:

Apparatus for preventing the surreptitious

supply of oil, liquid fuel or the like comprising a vessel forming a reservoir and a pump therefor including a sectional liquid receiving 25 conduit having the usual cooperating suction and check valves in said conduit, the sections of said conduit being detachably connected between said valves, so as to constitute an operative pump only when connected, that 30 section containing the check valve extending within the vessel and being a unitary part thereof, and the outer section of the liquid receiving conduit receiving an enlarged part forming a pump cylinder, the wall of said 35 pump cylinder at its junction with the rest of said conduit being of irregular contour to prevent it constituting a seat for any improvised check valve which might be introduced into said cylinder.

40 In testimony whereof I have signed my name to this specification.

PETER BÖHLING.
